CLAIM

The ornamental design for a foil transfer device, as shown and described.

DESCRIPTIONFIG. 1 is a perspective view of a foil transfer device;
FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The evenly spaced broken lines depict portions of the foil transfer device that form no part of the claimed design.
